(57) **CLAIM**

I claim the ornamental design for a reinforced leg band, as shown and described.

DESCRIPTION

FIG. 1 is a perspective view of a reinforced leg band, showing my new design.

FIG. 2 is a front view of the design of FIG. 1.

FIG. 3 is a rear view of the design of FIG. 1.

FIG. 4 is a left side view of the design of FIG. 1.

FIG. 5 is a right side view of the design of FIG. 1.

FIG. 6 is a top view of the design of FIG. 1.

FIG. 7 is a bottom view of the design of FIG. 1.

FIG. 8 is a front view showing additional details of an environment in which the design can be used; and,

FIG. 9 is a perspective view showing additional details of an environment in which the design can be used.

The broken lines shown in the drawings illustrate portions of the article that form no part of the claimed design.

1 Claim, 6 Drawing Sheets
